UNITED STATES PATENT OFFICE.

RAYMOND P. ALMSTEAD, OF ROCHESTER, NEW YORK, ASSIGNOR TO TAYLOR-SHANTZ COMPANY, OF ROCHESTER, NEW YORK, A CORPORATION.

REEL OR SPOOL.

1,361,802.

Specification of Letters Patent. Patented Dec. 14, 1920.

Application filed April 11, 1919. Serial No. 289,224.

To all whom it may concern:

Be it known that I, RAYMOND P. ALMSTEAD, a citizen of the United States, and resident of Rochester, in the county of Monroe and State of New York, have invented certain new and useful Improvements in Reels or Spools, of which the following is a specification.

The present invention relates to reels or spools, the present embodiment being designed for a reel for use in holding films for use in moving picture apparatus, an object of this invention being to provide a construction in which a hub having an inner core or bearing is detachably connected to the flanges, so that the hub and flanges may be separated for the purpose of more compactly holding them in the shipping cases or boxes.

15 To this and other ends the invention consists of certain parts and combinations of parts, all of which will be hereinafter described, the novel features being pointed out in the appended claims.

20 In the drawings:

Figure 1 is an axial section through a reel embodying the present invention;

Fig. 2 is a view of one face of the flanges of the reel;

30 Fig. 3 is a view of one side of the hub;

Fig. 4 is an end view of the hub;

Fig. 5 is an axial section through another embodiment of the invention;

Fig. 6 is a section through the reel shown 35 in Fig. 5 transversely of the axis of the reel;

Fig. 7 is a view of one side of the reel of the hub shown in Fig. 5; and

Fig. 8 is an end view of the hub shown in Fig. 5.

40 Referring more particularly to the embodiment of the invention shown in Figs. 1 to 4 inclusive of the drawings, 1 indicates the flanges which are detachably connected to the hub. The hub in this form consists of

45 an outer member or drum 2 formed of sheet metal with a spring lip 3 thereon by which the film is secured. Concentrically arranged within this outer member or drum is a bearing or core member 4 also formed in this 50 instance from sheet metal. The inner and outer members 2 and 4 are held in spaced relation by two plates or disks 5, the ends of the core member being extended through the disks and rolled or spun over the outer 55 faces of the latter as at 6, while the ends of

the drum 2 are provided with bendable tongues or lips 7 which are projected through slots in the disks 5. The hub is detachably secured to the flanges 1 and to this end the disks 5 abut the inner faces of the 60 flanges 1 which are provided with openings 8 at their centers so that a key or shaft may be introduced into the core or bearing portion 4. The flanges are also provided with an annular series of slots 9 concentric with 65 the opening 8 and into these slots the tongues 7 on the hub are fitted, being afterward bent into contact with the outer faces of the flanges so that the flanges are held to the hub.

70 In the embodiment shown in Figs. 5 to 8, the hub is also detachably engaged with the flanges and comprises an outer drum 2^a secured at its ends by tongues 2^b to end plates 5^a which are also connected by the bearing 75 member or core 4^a whose ends are flared outwardly at 6^a on the outer faces of the plates. The plates 5^a are projected at their edges beyond the circumference of the drum 2^a and these projecting edges are in this instance 80 notched at 10. The plates 5 rest against the opposed faces of the flanges 1^a near the center of the latter, the flanges having openings 8^a opposite the ends of the core 4^a and also having a series of tongues 11 struck up on 85 their inner faces. These tongues are adapted to be passed through the notches or recesses 10 in the end plates so that upon the relative relation of the hub and the flanges about the axis of the hub, the tongues will 90 engage the end plates and overhang the same in the manner shown in Fig. 6. In order to secure the hub and the flanges against relative turning, a locking device 95 may be employed at each end of the hub, this device in this instance consisting of a tongue 12 struck up from the metal of the flanges and adapted to enter one of the notches 10 in order that the locking may be 100 effected.

105 From the foregoing it will be seen that there has been provided a hub made of an inner core or bearing member and an outer drum both being formed of sheet metal and held in properly spaced relation by end plates, this hub being detachably connected with the flanges. By this construction the flanges may be packed separately from the hub making it possible to ship the reel in a knock-down condition, thus not only sav- 110

ing in the cost of shipping but also preventing injury to the reel in shipping.

What I claim as my invention and desire to secure by Letters Patent is:

5. 1. The combination, in a reel or spool, of a pair of flanges, a hub separate from the flanges comprising a sheet metal drum and sheet metal end plates secured to the opposite ends of the drum, the end plates and the 10 drum carrying means which interlock to hold the reel parts together.
2. The combination, in a spool or reel, of a pair of flanges with a hub connected to the flanges and comprising a pair of end plates 15 separate from the flanges, a bearing tube secured at its opposite ends to said end plates, and a drum separate from the bearing surrounding said bearing and also secured at its opposite ends to the end plates, 20 the flanges having openings opposite the ends of the bearing through which a shaft may be introduced in the bearing.
3. A hub for spools or reels comprising a drum, a core formed separately from and 25 arranged in the drum, and end plates secured to the opposite ends of the drum and the core combined with two flanges separate from the end plates having interlocking connection with the hub and provided with 30 openings at the ends of the core.
4. The combination, in a spool or reel, of two flanges with a hub, one of which interlocks with the other by a relative rotation about the axis of the hub, the hub comprising 35 a drum, a central core formed separately from the drum, and a pair of end plates separate from the flanges to which the ends of the drum and the core are secured.

5. The combination, in a spool or reel, of two flanges and a hub, one of said parts having tongues to interlock with the other by a turning movement about the axis of the hub and a latch carried by one of said parts and interlocking with the other when 45 the parts have been turned to a certain position.

6. The combination, in a spool or reel, of a pair of flanges having their inner faces provided with overhanging tongues, with a hub 50 having end plates formed with notches to receive said tongues, the hub and flanges being rotatable to carry the end plates under the tongues, and locking tongues adapted to enter said notches to hold the hub and 55 flanges against relative turning.

7. The combination, in a spool or reel, of a flange having its inner face provided with tongues, with a hub having end plates formed with notches to receive said tongues, 60 the hub and flange being relatively rotatable to carry the end plates under the tongues, and a locking device on the flange adapted to enter one of the notches in the end plate to prevent the relative turning. 65

8. The combination, in a spool or reel, of a pair of flanges, each having its inner face provided with a plurality of tongues, with a hub comprising an outer drum, an inner core and end plates secured to opposite ends 70 of the core and the drum and projecting beyond the drum, the projecting portions of the end plates having notches to receive the tongues, the hub being rotatable relatively to the flanges to cause the end plates to interlock with the tongue. 75

RAYMOND P. ALMSTEAD.
